UNITED STATES PATENT OFFICE.

CHARLES CAREY MANKER, OF DES MOINES, IOWA.

OIL-BURNER.

1,344,421.

Specification of Letters Patent. Patented June 22, 1920.

Application filed April 3, 1917, Serial No. 159,483. Renewed May 19, 1920. Serial No. 382,685.

To all whom it may concern:

Be it known that I, CHARLES C. MANKER, a citizen of the United States, and a resident of Des Moines, in the county of Polk and State of Iowa, have invented new and useful Improvements in Oil-Burners, of which the following is a specification.

My invention relates to improvements in oil burners, and it consists in the combinations, constructions and arrangements herein described and claimed.

An object of my invention is to provide an oil burner which may be applied to various uses, such as cook stoves, heating stoves, furnaces and the like, and by means of which substantially perfect combustion is effected, thereby economizing in fuel.

A further object of my invention is to provide an oil burner which dispenses with the need of auxiliary pressure such as that supplied from compressed air. The means by which this is accomplished consists in an arrangement whereby the pressure of the gasified fuel is sufficient to force the gas into the interior of the combustion chamber and at the same time to entrain a sufficient quantity of air so as to effect complete combustion.

A further object of my invention is to provide a burner of the type described which consists of relatively few parts and which, is, therefore, not liable to get out of order.

Other objects and advantages will appear in the following specification and the novel features of the invention will be particularly pointed out in the appended claims.

My invention is illustrated in the accompanying drawings forming part of this application, in which:

Figure 1 is a side view of the device, certain parts being shown in section;

Fig. 2 is a plan view of the device;

Fig. 3 is a perspective view, showing certain parts in position ready for assembling; and

Fig. 4 is an enlarged section through a portion of the burner.

In carrying out my invention I provide a base 1, this being preferably a metal casting. The base may be provided with legs 2 and contains two chambers 3 and 4, respectively, (see Fig. 3), a partition 5 separating these chambers but terminating short of the rear, as shown in Fig. 1, so as to pro-

vide a communicating passage 6. The top 7 of the base portion is provided with an upstanding rim 8 preferably of rectangular shape, this rim and the top constituting a receptacle for the liquid fuel when the device is to be started. An asbestos or other non-inflammable wick 9 is provided, as shown in Fig. 1.

An upper portion 10 is provided, which rests on the lower portion, the flanges 8 serving as guide flanges so as to bring the sides and one end of the upper and lower portions in alinement. The upper portion has a grate 11 and at one end has an opening 12.

Referring now particularly to Fig. 4, I have shown therein in detail the means for feeding the fuel oil. A pipe 13 communicates with the compartment 4 through an opening 14 in the top 7 of the base portion (see Fig. 3). This pipe is the outlet pipe. An inlet pipe 15 (see Fig. 1) communicates with the compartment 3 through an opening 16. A removable plate 17 is provided for closing the ends of the chambers 3 and 4. The fuel enters the pipe 15, passes through the chamber 3, through a passage 6, thence through the chamber 4 and into the pipe 13. At 18 I have shown a needle valve which is manipulated by a hand wheel 19 which permits the liquid fuel to flow through a pipe 20 into the receptacle containing the wick 9. Normally, the needle valve 18 is closed. Above the valve casing is a float chamber 21 having a float 22 which is provided with a valve 23 arranged to control the pipe 24 leading to the main valve casing 25. The valve casing 25 is provided with a valve 26, which, in this instance, is shown as a needle valve and which is manipulated by a handle 27.

Threaded on one end of the valve casing 25 is a conical shaped member 28 which is provided with a series of openings 29 on the sides thereof. The cone 28 is provided on the interior with a series of inwardly extending flanges 30, these flanges having inclined portions 31 which are circular in contour and which are progressively larger from the needle valve toward the opposite end of the cone. On the outside of the cone is a revoluble cover 32 having openings 33 which may register with the openings 29 in certain positions of the cover, but which may vary the effective area 110

of the openings 29 when the cover is re-volved. A lock nut 34 is provided for se-curing the revoluble cover in position. At the end of the cone is a sheet of wire net-ting 35.

From the foregoing description of the various parts of the device the operation thereof may be readily understood. As has been stated before, in order to start the de-vice 10 the liquid fuel is permitted to flow through the pipe 20 by turning the handle 19. The asbestos wick soaks up the fuel and may be lighted by thrusting a match through the bars of the grate 11 or by raising the 15 upper portion 10 slightly. Normally, the chambers 3 and 4 as well as the float cham-ber 21 are filled with oil, the oil entering the float chamber 21 as far as the float will permit it. When the float rises the valve 23 20 is seated, thus preventing the passage of oil into the valve casing 25 and also stopping the flow of oil into the chamber 3 through the inlet 15.

After the fuel has been ignited the oil 25 chambers 3 and 4 become heated to such an extent that the oil is vaporized. When this occurs the vapor will force the oil back out of the float chamber and will permit the float to descend. The gas will pass then into the 30 valve casing 25 and past the needle valve. It will be forced past the flanges 30 which tend to keep the stream of gas converged and to prevent its diverging toward the sides of the cone. Air is entrained, being 35 drawn in through the openings 33 and 29, and more air is drawn in as the gas passes through the cone. The mixture of air and gas is passed through the netting and into the combustion chamber, where it is ignited 40 and consumed, the flames passing out through the grate 11. When the gas is turned off by means of the handle 27 and the burner cools down the oil will again enter the chambers 3 and 4 and pass up into 45 the float chamber 21, thus closing the valve 23 and preventing the flow of the liquid fuel past the needle valve when the device is again ignited, until the oil has been suffi-ciently heated to vaporize.

50 It will be noted that the device operates under its own pressure. This is compara-tively slight, it being only necessary to ele-vate the oil tank or to place upon the oil tank a slight pressure to resist the pressure 55 of the gas when the oil has been gasified or vaporized. The device is simple in construc-tion and, being automatic in operation, it re-quires very little attention, while the com-bustion effected by the arrangement of parts 60 is such that very little soot or carbon is deposited in the combustion chamber. On the other hand the device develops high heat and is especially desirable for those furnaces which require high temperature 65 for their proper operation.

Having thus described my invention, I claim:

1. A liquid fuel burner comprising a hollow base portion containing an oil chamber, an inlet communicating with the oil cham-ber, an outlet leading from said oil chamber, 70 a float chamber connected with said oil chamber, a combustion chamber disposed in close proximity to said oil chamber for heat-ing the latter, and a mixing device com-municating at one end with the float cham-ber and discharging at the other end into 75 said combustion chamber.

2. An oil burner comprising a base por-tion having an oil chamber, an inlet and an 80 outlet for said oil chamber, a float chamber communicating with said outlet, a valve cas-ing communicating with said float chamber, a valve controlled by the float in said float chamber, a combustion chamber disposed 85 upon said oil chamber, and a mixing device carried by said valve casing and discharg-ing into said combustion chamber.

3. An oil burner comprising a base por-tion having an oil chamber, an inlet and an 90 outlet for said oil chamber, a float chamber communicating with said outlet, a valve cas-ing communicating with said float chamber, a valve controlled by the float in said float chamber, a combustion chamber disposed 95 upon said oil chamber, a mixing device car-ried by the said valve casing and discharg-ing into said combustion chamber, and a grate carried by said combustion chamber at 100 the top thereof.

4. An oil burner comprising a base hav-ing an oil chamber, said oil chamber being provided with an inlet and an outlet, a com-bustion chamber disposed above the base, an oil recentacle carried by the base within the 105 combustion chamber, means for supplying oil to said oil recentacle, a float chamber communicating with said oil chamber, a valve within said float chamber, a valve cas-ing communicating with said float chamber, 110 communication between said valve casing and said float chamber being controlled by said valve, a main control valve in said valve casing, a mixing device carried at one end of said valve casing, the opposite end of 115 said mixing device being directed toward said combustion chamber for discharging fuel into said chamber, and a grate car-ried by the combustion chamber at the top thereof. 120

5. An oil burner comprising a valve cas-ing, a valve within said casing, a mixing de-vice carried by said valve casing at one end thereof, said mixing device comprising a conical shell having openings in its sides, a 125 series of flanges having circular openings, said flanges having angularly inclined por-tions, and means for varying the effective area of the openings in the conical shell.

6. An oil burner comprising a valve cas- 130

ing, a valve within said casing, a mixing device carried by said valve casing at one end thereof, said mixing device comprising a conical shell having openings in its sides, a series of flanges having circular openings, said flanges having angularly inclined portions, means for varying the effective area

of the openings in the conical shell, said last named means comprising a conical cover having openings arranged to register with the first named openings, said cover being revoluble, and means for locking the cover in revolved position.

CHARLES CAREY MANKER.
